UNITED STATES PATENT OFFICE

CHARLES L. DEAN, OF DENVER, COLORADO, AND LEWIS D. HILTON, OF SAN ANTONIO, TEXAS, ASSIGNEES, BY MESNE ASSIGNMENTS, TO WILLIAM A. TROUT, OF LOS ANGELES, CALIFORNIA, AND CHARLES R. BUTLER AND CHESTER A. RASMUSSEN, BOTH OF LONG BEACH, CALIFORNIA

CONTROL HEAD FOR OIL WELLS

Application filed January 21, 1929. Serial No. 333,928.

This invention relates to control heads for oil wells and it is an object of the invention to provide a control head of very simple construction and of great practicability in use, 3 that is readily applied to a well casing, and which can be adjusted for the renewal of packings or worn parts without disturbing the casing with which it is associated.

A distinctive feature of the invention consists in the provision of a method for suspending a casing in the well by means that are at all times plainly visible and accessible, and an important characteristic of this feature resides in a metal-to-metal joint between 15 outer and inner members of the head that provides a practically gas tight connection without the aid of packing devices usually found in control heads of this type.

Another object of the invention is to provide in a control head of the above stated character, means to automatically center a casing with relation thereto.

A further object is to provide in a control head, an outlet for gases from between 25 strings of casing, below the means by which the head is packed to render it gas tight and still other objects reside in details of construction and in novel combinations and arrangements of parts, as will appear in the 30 course of the following description.

By the use of the improved control head, the "stretch" may be taken out of the casing in a very simple manner, and all adjustments are easily accomplished because of the several 35 parts comprised in the head being accessible at the outside of the same.

In the accompanying drawings, in the several views of which like parts have been similarly designated,

Figure 1 represents a partially sectional elevation of the improved control head as applied to a well casing,

Figure 2, a plan view of a supporting member forming a part of the construction.

Figure 3, a side elevation of the part shown in Figure 2,

Figure 4, a composite view drawn to an enlarged scale and showing partially in section and partially in elevation, the improve-

ments applied to a base section of a well structure,

Figure 5, a sectional elevation showing a plurality of the control heads in cooperative association for the support of concentric well 55 tubings,

Figure 6, a fragmentary section on the line 6—6, Figure 5, and

Figure 7, a similar section taken along the line 7—7, Figure 5.

Referring first to Figure 1 of the drawings, the reference numeral 19 designates a tubing or casing suspended by means of the control head.

The head comprises a base element 8 which in practice, is secured in place to provide a stable support for the suspension element by means of which the casing is suspended in the well.

The base element, as shown in Figure 1, 70 has a circular body exteriorly screw-threaded at its lower end and provided at its upper end with an outwardly projecting flange 10.

The element has in its body portion, screw-threaded openings 17 for the outlet of gases 75 from the well into conduits 18 which by connection with the openings, conduct the gases to a distant point of escape.

In case the base element is of reduced height as is sometimes required in order to 80 adapt the head for use as a lower section of a stack of heads, the outlet opening may be made narrow at the inside of the element and tapered to the outside of the same, as illustrated at 15 in Figures 5 and 6. Otherwise 85 the openings are of uniform diameter, as indicated in Figure 7.

The flange 10 of the element may be provided with concentric grooves for the application of packing rings 12 and 13, when it is desired to provide a gas tight joint around the suspension element, as will hereinafter be more fully described.

The base element is chamfered at the upper end of its bore, as shown at 14, to provide a seat for self-centering of the member of the suspension element, which is in direct engagement with the base element.

The chamfer on the base element is also advantageous in that it prevents the casing as 100

it is lowered into the well, from being stopped in its descent by collars on the casing catching with sharp edges in the opening through which the casing passes.

5 The suspension element, hereinbefore referred to, consists of two members 20 and 21. The member 20 consists of a tubular collar, internally screw-threaded at its ends and circumferentially grooved as at 20a for its connection with the other member.

10 This other member 21 comprises a ring fitted into the groove 20a of the member 20 and projecting outside the same for the support of the suspension element upon the base element.

15 The ring is made in two halves, as shown in Figure 2, and its lower portion is reduced in diameter and chamfered at its lower exterior edge as at 21a, to enter into the chamfered portion 14 of the bore of the base element. The portion of the ring above its reduced portion constitutes a shoulder 22 which rests upon the base element for the support of the suspension element.

20 The ring is furthermore provided with tapped holes 24 for the application of tools that may be required to assist in placing the ring within the groove of the collar, under gas-pressure, and the ring has an external groove 23 for the application of a wire band when under similar conditions it is necessary to secure the halves of the ring in place.

Under ordinary conditions, the head as hereinabove described, is complete for the suspension of a casing in a well, and, in conjunction with other similar heads, for the suspension of two or more concentric casings when the well is of greater depth.

If, however, the gas pressure in an oil well 40 to which the head is applied, has enough force to lift the suspension element off its seat on the base element, it is necessary to provide suitable means for holding the suspension element against excessive upward motion, and to pack the joint between the two elements against the escape of gases.

An efficient and practical packing device has been shown in the drawings as consisting of a ring 27 coextensive with the flange 10 of the base element and resting upon the before mentioned packings 12 and 13 placed in the grooves of the flange. The packing ring 27 and the flange 10 have registering bolt holes and are fastened together by means of bolts 53 and nuts 53a.

The packing ring 27 is recessed to admit the portion of the ring 21 projecting outside the groove of the collar 20 and it is further recessed as at 29, for the application of a packing that engages the collar above its groove. A gland 31 drawn into the groove by nuts on stud bolts 54 causes the packing to expand against the collar.

It is to be observed that the packing ring 65 27 loosely embraces the ring 21 of the sus-

pension element. It has no function whatsoever in the suspension of the casing, and if the gas pressure in the well is slight it may, as stated hereinbefore, be entirely omitted.

It will be noted that the packing device 70 may be applied after the casing is suspended from the base element of the head and without disturbing the position of the casing or any part of the head.

Figure 4 of the drawings shows a modification 75 of the base element of the head for its support on a foundation around the mouth of the well.

The base element has, to this end, a bottom flange 47 provided with an upturned rim 38 and strengthened by webs 39. The base element has been shown as supported upon a concrete foundation 40 and in fluid tight engagement with a casing 5 that lines the wall of the well.

80 The element is secured upon its foundation by nuts 46 on stud bolts 45 that project through sleeves 44 formed on the lower flange of the element.

85 The base element may be provided with outwardly projecting hooks 9 which facilitate moving the element in assembling and which also may be used to clamp the element in place.

90 In Figure 5 has been illustrated the method of supporting one control head upon another when there is more than one casing or tubing in a well of greater depth. The base element of the upper head is screwed into the top of the collar of the lower head, all the 100 constituent parts of the upper head being reduced in diameter with respect to the lower head. It will be understood that in this manner several heads may be assembled in one stack.

105 The base element of the lowermost head has been shown as connected with the outer casing or lining of the well by means of a screw threaded union 6.

110 In order to take the "slack" out of a casing after it has been lowered into the well until it has reached the bottom thereof, the casing is pulled up until its bends are straightened. A mark is then made on the pipe to indicate the length to which it must be reduced to hold it permanently in suspension.

115 After the casing has been reduced in length by cutting it at the mark, it is fastened at the lower end of the collar of the suspension element, the sectional ring is placed in the groove of the collar and the suspension element thus assembled is placed upon the respective base element.

120 The packing device may be subsequently applied if so desired.

125 It is a distinctive feature of the invention that all the parts thereof may be assembled above the surface of the ground, without the necessity of working in what is com-

monly known as the "cellar", which frequently is very hazardous because of poison gas in the well, and without interference by gas pressure in the well which often times is 5 very heavy.

In this connection, it is observed that the present construction differs from others in that the lower edge of the supporting ring is under all conditions in plain sight of the 10 operator when it is in place, thereby facilitating assemblage, removal and adjustment. The metal-to-metal joint between the inner and outer members of the control head, established by medium of the ring, is in many 15 cases fully efficient for the suspension of the casing with little or no detrimental escape of gases, thereby rendering the use of packing devices unnecessary under certain conditions, and this metal-to-metal joint is in a 20 plane approximately coinciding with the upper end of the outer member, which is in full view and always accessible from the outside of the structure.

The position of the suspension means furthermore eliminates the greater part of loss 25 of slack after the rings are put in place, particularly when the inside casing is fast at or near its bottom.

The chamfers of the two elements cooperate to automatically center the casings one 30 within another, thereby avoiding manual adjustment.

The position of the escape openings in the base element of the head permits of controlling 35 the escape of the gas from the moment that the two elements are placed in position.

The packings are easily replaced without disturbing the casing or any part of the head proper.

40 The base element shown in Figure 4 may have a concentric series of beveled lugs 48 for its support on the foundation. The bevel of these lugs centers the element with relation to the casing 5 that engages a packing 45 50 set in a concentric groove of the element. The bolts 45 help to center the base element and secure it in place when the nuts 46 are applied to their threaded extremities.

What we claim and desire to secure by 50 Letters Patent is:

A control head construction for oil wells including the combination with an outer casing and an inner casing spaced therefrom, a base element, a shoulder on the base element, 55 a coupling connecting the inner casing sections and having a groove, a load carrying ring interlocked with said groove and resting on said shoulder, a packing flange overlying the base element and ring, fastenings 60 for securing the packing flange and base element together to anchor the inner casing to the outer casing and thereby prevent upward movement of the inner casing under gas pressure, said packing flange having a recess 65 in its upper face above the load carrying

ring to provide a packing receiving cavity, a packing in said cavity, and a packing gland cooperating with the cavity formed by said recess and the coupling to compress the packing held therein.

In testimony whereof we have affixed our signatures.

CHARLES L. DEAN.
LEWIS D. HILTON.
